CONTAINER AND SAFETY CLOSURE THEREFOR
Benjamin K. Milbourne, Los Angeles, Calif., assignor to
K.C.K. Holding Company, a partnership
Filed Oct. 11, 1963, Ser. No. 315,578
4 Claims. (Cl. 215—9)

This invention relates to a bottle or jar having a safety closure and more particularly to such a structure requiring, to open, manipulations which are difficult for small children.

It is an object of this invention to provide a safety closure, all parts of which may be made of an inexpensive plastic, if desired.

It is a further object of this invention to provide a container which is of conventional construction, insofar as it is equipped with the usual threads at the neck thereof, and a safety closure therefor which may be relatively easily manipulated by adults but only with difficulty by small children so that medicines, corrosive substances, and poisons may be placed therein with relative safety.

It is yet another object of this invention to provide an assembly of the aforementioned type requiring a minimum of parts.

Other objects and advantages of this invention, if not specifically set forth, will become apparent from the description which follows.

In the drawings accompanying this application:

FIGURE 1 is an exploded view in perspective of the cover assembly of this invention.

FIGURE 2 is an assembled view in perspective of the cover assembly of this invention with the locking key in place.

FIGURE 3 is a fragmentary side elevation, partially in section, showing the assembly of this invention with the locking means in place.

FIGURE 4 is a view similar to FIGURE 3 with the locking means not in place so that the safety feature is in effect.

Generally, this invention comprises a container and safety closure therefor, the entire assembly including a bottle or other container having a cylindrical neck at the top end thereof, which neck has integral threads. The closure assembly includes an interior cap element including a planar top and an integral cylindrical collar having integral internal threads mating with the threads of the neck of the container, the top of the interior cap preferably being relatively slick and having a notch at the intersection of the planar top and the collar, the notch extending perpendicular to the planar top of the interior cap element and radially of the cap element. The notch should extend only partially through the interior cap element whereby the interior cap element can be used to seal the container. There is also provided as part of the closure assembly an exterior cap element having a planar top and a collar fitting loosely concentrically about the collar of the interior cap element for rotation relative thereto. The exterior cap element has a slot at the intersection of the planar top and the collar, the slot extending perpendicular to the planar top of the interior cap element and radially of the element. Finally, there is provided a key which is of relatively small cross-section and which is capable of fitting through the slot and into the notch whereby to lock the two cap elements against relative rotation. Preferably, the key is attached to the exterior cap element by means of a resilient flexible strap to permit the key to be manipulated to register with the slot and notch.

Referring now to the drawings wherein like characters refer to like parts throughout, there is shown a bottle or jar 10 which has continuous helical threads 12 about

2

its cylindrical neck so that an ordinary cap might be screwed down tightly over the mouth. The container body 10 is conventional; it is the closure member which is the subject of this invention. Thus, the safety closure member of this invention requires no costly special bottle structure. The closure assembly resembles in appearance a conventional cover having internal threads 14 which register with the jar threads 12. The entire closure assembly consists of at least two parts including the cylindrical exterior cap element 16 having a planar top 18 and an integral cylindrical collar 20. These interior threads mate with the threads on the neck of the container. The element 16 has one or more notches 22 at the intersection of the planar top 18 and the collar 20, the notches extending perpendicular to the planar top and radially of the collar. The notches should extend only partially through the interior cap 16 whereby the interior cap element can be used to seal the contents within the container. To assist in this sealing action, a conventional paper disk 34 may be used.

There is also provided an exterior cap element, generally 26, having a planar top 28 and an integral collar 30 fitting loosely concentrically about the collar of the interior cap element for rotation relative thereto. As shown in the sectional views, there is provided a small lip 32 on the exterior cap for locking the interior and exterior cap elements against axial movement. Each of these cap elements preferably is of a stiff plastic and may be forced together and will remain in a unitary relationship unless forceably separated. The exterior cap element has a slot 34 extending entirely through the exterior cap element whereby to permit access to the notches in the interior cap element through the slot. The slot is perpendicular to the surface 28 and extends radially of the collar 30. Preferably, the slot and notches are of the same width.

Finally, there is provided a key 36 secured by a flexible strap 38 to the entire assembly and preferably to the exterior cap element. A preferred structure involves an integral exterior cap 26 and key 36 connected by a resilient strap 38 which normally urges the key out of the locking position of FIGURES 2 and 4.

In operation, the key normally tends to remain in the position shown in FIGURES 1 and 3 as the strap 38 tends to straighten out when not urged in one direction or another and the assembly would not be found by small children with the key already in place. Rather, the interior and exterior cap elements 16 and 26 rotate freely relative to one another. When it is desired to remove or apply the cap, the key 36 is pressed into the slot 34 and the exterior cap 26 rotated until the key drops into a notch 22. It will be seen that further rotation of the cap assembly will either remove or apply the cap to the container.

Obviously, many modifications and variations may be made without departing from the spirit and scope of this invention, and therefore only such limitations should be made as are indicated in the appended claims.

I claim:

1. An assembly including a container and safety closure therefor including in combination:

(a) a container having a cylindrical neck at the top thereof and integral threads molded in the cylindrical neck;

(b) an interior cap element including a planar top and a cylindrical collar having internal threads mating with the threads on the neck of said container, the top of said interior cap element having at least a single notch therein;

(c) an exterior cap element having a planar top and a collar fitting loosely concentrically about the collar of the interior cap element for rotation relative

thereto, said exterior cap element having a slot there-through positioned for registry with said notch in the said interior cap element, said slot extending entirely through said exterior cap element whereby to permit access to said notch; 5
(d) and a key of a sufficiently narrow width to fit through said slot and into said notch, said key being attached to said assembly by means of a flexible strap to permit said key to be manipulated to register with said slot and notch, said strap being integral with 10 said exterior cap element.

2. An assembly including a container and safety closure therefor including in combination:

- (a) a container having a cylindrical neck at the top end thereof and integral threads molded in the 15 cylindrical neck;
- (b) an interior cap element including a planar top and a cylindrical collar having internal threads mating with the threads of the neck of said container, the top of said interior cap element having at least a 20 single notch therein at the intersection of said planar top and said collar, said notch extending perpendicularly to the planar top of said interior cap element and radially of the collar thereof;
- (c) an exterior cap element having a planar top and a 25 collar fitting loosely concentrically about the collar of the interior cap element for rotation relative thereto, said exterior cap element having a slot at the intersection of the said planar top and said collar, said slot extending perpendicularly to the planar top 30 of said exterior cap element and radially of the collar thereof, said slot extending entirely through said exterior cap element whereby to permit access to said notch of said interior cap element through said slot in said exterior cap element; 35
- (d) and a key of a sufficiently narrow width to fit through said slot and into said notch, said key being attached to said assembly by means of a resilient, flexible strap to permit said key to be manipulated to register with the said slot and notch, said strap normally urging said key out of registry with said slot and notch, said strap being integral with said exterior cap element.

3. An assembly including a container and safety closure therefor including in combination:

- (a) a container having a cylindrical neck at the top end thereof and integral threads molded in the 45 cylindrical neck;
- (b) an interior cap element including a planar top and a cylindrical collar having internal threads mating with the threads of the neck of said container, the top of said interior cap element having at least a 50 single notch therein at the intersection of the said planar top and said collar, said notch extending perpendicularly to the planar top of said interior cap element and radially of the collar thereof, said notch extending only partially through said interior cap element whereby said interior cap element may be used to seal the said container;

(c) an exterior cap element having a planar top and a collar fitting loosely concentrically about the collar of the interior cap element for rotation relative thereto, said exterior cap element having a slot at the intersection of the said planar top and said collar, said slot extending perpendicularly to the planar top of said exterior cap element and radially of the collar thereof, said slot extending entirely through said exterior cap element whereby to permit access to said notch of said interior cap element through said slot in said exterior cap element, said exterior cap element having a lip along the lowermost edge of the collar thereof to provide means for locking the interior and exterior cap element together; 5
(d) and a key of a sufficiently narrow width to fit through said slot and into said notch, said key being attached to said assembly by means of a resilient, flexible strap to permit said key to be manipulated to register with the said slot and notch, said strap normally urging said key out of registry with said slot and notch, said strap being integral with said exterior cap element.

4. An assembly including a container and safety closure therefor including in combination:

- (a) a container having a cylindrical neck at the top thereof and integral threads molded in the cylindrical neck;
- (b) an interior cap element including a top and a cylindrical collar having internal threads mating with the threads on the neck of said container, said interior cap element having a relatively depressed portion in the exterior surface thereof;
- (c) an exterior cap element having a planar top and a collar fitting loosely concentrically about the collar of the interior cap element for rotation relative thereto, said exterior cap element having a passage extending entirely therethrough, said passage being positioned so that a key extending through the said passage may be caused to register with said relatively depressed portion of said interior cap element; 30
- (d) and a key of a sufficiently narrow width to fit through the said passage and to register with said relatively depressed portion of said interior cap element, said key being attached to the said assembly by means of a flexible strap to permit said key to be manipulated to enter said relatively depressed portion and to prevent relative movement between the interior and exterior cap elements, said strap being integral with said exterior cap element.
